UNITED STATES PATENT OFFICE.

JOSEPH HENRY MCINTIRE, OF BROOKLYN, NEW YORK, ASSIGNOR OF ONE-HALF TO
LOUIS H. KAPLAN, OF BROOKLYN, NEW YORK.

GUMMED-TAPE-SEALING MACHINE.

Application filed September 16, 1924. Serial No. 738,051.

To all whom it may concern:

Be it known that I, JOSEPH H. MCINTIRE, a citizen of the United States, and a resident of the city of New York, borough of Brooklyn, in the county of Kings and State of New York, have invented a new and Improved Gummed-Tape-Sealing Machine, of which the following is a full, clear, and exact description.

10 This invention relates to gummed tape sealing machines and more particularly to that class of apparatus in which tape having a gummed or adhesive surface is drawn from a roll and moistened and torn off in suitable lengths for use as sealing devices for packages and the like.

20 An object of the invention is to provide a machine of this character having a cradle lift through which the tape is laced and which is provided with a movable weight operating to hold the cradle in either of its extreme positions and to perform its functions automatically in accordance with the movement of the cradle by the operation of the tape.

25 A further object is to provide in a machine of this character a pivoted cradle through which the tape is laced, and having a straight edge against which the tape is torn, together with an automatic drop functioning to hold the tape away from the tearing edge and in position to be grasped for operation.

30 A further object is to provide improved means for supporting a roll of gummed paper which permits the use of any desired width of roll.

35 A further object is to provide a machine of this character which permits the proper functioning thereof without subjecting any portion of the machine to an accumulation of gum or adhesive so that the machine is maintained clean and sanitary at all times.

40 With these and other objects in view, the invention consists in certain novel features of construction and combinations and arrangements of parts which will be more fully hereinafter described and pointed out in the claims.

In the accompanying drawings—

Figure 1 is a top plan view of my im-

proved machine, showing the tape in the operation of receiving moisture from the wet roll;

55 Figure 2 is a view in longitudinal section on the line 2—2 of Figure 1, with the parts in the position above described;

Figure 3 is a view in longitudinal section on the staggered line 3—3 of Figure 1, showing the cradle in elevated position, and in dotted lines indicating the tearing position of the tape;

Figure 4 is a view in transverse section on the line 4—4 of Figure 1;

Figure 5 is a fragmentary view in section on the line 5—5 of Figure 4.

A represents the base of my improved machine which preferably constitutes a platform 1 supported in elevated position by side flanges 2 and having a box 3 at its forward end in which a tank 4 is located. This tank 4 is adapted to contain water or other moistening element and supports a roll 5, the lower portion of which extends into the water so that when the roll is revolved its surface will carry sufficient moisture to the tape, the latter indicated by the reference numeral 6.

70 In order to prevent an accumulation of adhesive on the front portion of the box 3, I preferably bevel this front portion, as indicated at 7. On the rear portion of the platform 1 I provide a pair of uprights 8 and 9 supporting a roll 10 of gummed tape, preferably of paper, and of suitable width. The upright 8 is preferably fixed to the platform while the upright 9 is adjustable and removable so as to allow for different widths of tape. The upright 9 is preferably provided with an angular foot 9' which more or less securely clamps the platform 1, and an arbor 11 projects through the upper portions of both of these uprights 8, 9, and has screw-threaded ends for the reception of nuts 12 to hold the arbor in place.

75 80 85 90 95 100 A spool 13 is preferably located in the center of the roll 10 with clamping plates 14 at opposite sides of the roll and spacing sleeves 15 located against the plates 14, so that when the nut 12 located against the outer face of an upright is screwed home the roll will be in proper position. It is obvious that with a construction of this

kind the parts may be readily separated for the insertion of a new roll as occasion may require.

B represents my improved cradle, which constitutes a U-shaped frame 16 having an angle bar 17 at its forward end, one member of this angle bar constituting a straight edge 18 against which the tape 6 is adapted to be torn. The frame 16 has a rearwardly projecting arm 19 fixed thereto and projecting at an angle therefrom, and a bent rod 20 has one end thereof secured to one end of the arm 19 and its other end secured to an angle bracket 21 on one side of the frame 16. The greater portion of this rod 20 is straight and supports a movable weight 22, and cushions 23 are located on the rod 20 to receive the blows of the weight and to cushion the shock.

20 The cradle B is fulcrumed on a rod 24 which projects through the members of the frame 16 and is secured in brackets 25 to the platform 1. This rod 24 supports a tubular roller 26, and a series (preferably 3) of rollers 27 are mounted in parallelism in the frame 16 and between which the tape 6 is laced after it is passed under the roller 26.

An automatic drop 28 is supported by the frame 16 and constitutes a bail 29 pivotally mounted at its ends in the frame, as shown at 30, and its forward portion supporting a roller 31 adapted to engage the tape 6 in advance of the forward roller 27. The bracket 21 has a laterally extending lug 32 which is in the path of movement of the roller 31 so that in the event that the momentum of the movement of the cradle is sufficient to throw the drop device backwardly this lug 32 will be engaged with the roller and limit the movement of the drop so that the latter will fall to operative position when permitted.

Cushions 33 and 34 are provided on the platform 1. The cushions 33 are engaged by the frame 16 as the latter assumes its forward and downward position, and the cushion 34 is engaged by the arm 19 as the cradle assumes its rearward position so that the shocks of this movement are cushioned. Also it will be noted that the platform 1 has a longitudinal recess 35 therein to accommodate the arm 19 when it is in horizontal or rearward position.

The operation is as follows:

55 When it is desired to remove a length of moistened tape, the extremity of the tape is grasped between the thumb and fingers of the operator and it is drawn forwardly over the moistening roll 5. This pull on the tape will swing the cradle forwardly and downwardly to the position shown in Figure 2, and the weight 22 will slide forwardly on the rod 20 to maintain the cradle in this position. When the proper length of tape is drawn over the moistening roll the operator

swings the tape upwardly and slightly rearwardly against the tearing edge 18 of the cradle. This movement will cause the cradle to pivot rearwardly and assume the position indicated in Figure 3, the weight sliding 70 rearwardly on the rod 20 to hold the cradle in this position. A continued movement rearwardly and laterally of the tape will cause the same to be torn against the straight edge 18. After the length of tape is torn 75 off the automatic drop 28 will move downwardly against the tape causing the free end of the tape to move away from the bar 17 and remain in a position to be readily grasped for future use for repeated operation.

It will be noted that by reason of the construction above described the tape will be moistened only to the point where it is torn off, so that the free end of the remaining 85 tape is free from moisture and will not soil the fingers of the operator, nor adhere to any portion of the machine to interfere with its operation. The machine, therefore, remains perfectly free from an accumulation 90 of adhesive or gum and is ready for operation at all times.

Various slight changes and alterations might be made in the general form of the parts described without departing from my 95 invention, and hence I do not limit myself to the precise details set forth but consider myself at liberty to make such slight changes and alterations as fairly fall within the spirit and scope of the appended 100 claims.

I claim:

1. An apparatus of the character described, comprising a moistening device, a tape holding cradle having a tearing edge thereon and movable from one extreme position to another, and a movable weight adapted to hold the cradle in either of the extreme positions.

2. An apparatus of the character described, comprising a moistening device, a tape holding cradle having a tearing edge and movable from one extreme position to another, a rod on the cradle, and a weight mounted to slide on the rod and movable past the pivotal center of the cradle to hold the cradle in either of its extreme positions.

3. An apparatus of the character described, comprising a base, a tape carrying cradle pivotally mounted between its ends on the base and movable from one extreme position to another, a movable weight on the cradle adapted to hold the cradle in either of its extreme positions, and a moistening device onto which the tape is guided when the cradle is in one extreme position.

4. An apparatus of the character described, comprising a base, a tape carrying cradle pivotally mounted between its ends on the base and movable from one extreme

position to another, a movable weight on the cradle adapted to hold the latter in either of its extreme positions, a bar on the cradle constituting a tearing edge, a moistening device on the base and an automatic drop on the cradle normally holding the tape away from the bar.

5 5. A machine of the character stated, comprising a base, a moistening roll on the base, a cradle pivotally mounted on the base, a series of rolls on the cradle over which the tape to be moistened is laced, said cradle having a tearing edge at one end, a rod on the cradle, a weight movable on the rod 10 and adapted to hold the cradle in either of its extreme positions, and an automatic drop on the cradle engaging the tape and holding the free end of the tape away from the cutting edge when the cradle is in its rearward 15 position away from the moistening roll.

6. A machine of the character described, comprising a base, a box at one end of the base, a liquid tank in the box, a moistening roll in the liquid tank, a pair of uprights 20 connected to the base, one of which is movable and removable, said uprights adapted to support a roll of gummed tape, a cradle pivotally mounted on the base between the uprights and the moistening roll and having a tearing edge at its forward end, devices on the cradle supporting the tape, a rod connecting the respective end portions of the cradle, a movable weight on the rod, 25 cushions on the rod receiving the impact of the weight, cushions on the base receiving the impact of the cradle, a bail pivotally connected to the cradle, and a roller carried by the free end of the bail and constituting an automatic drop adapted to engage the free portion of the tape and to hold it away from the tearing edge.

35 7. A machine of the character described, comprising a base, a box at one end of the base, a liquid tank in the box, a moistening roll in the liquid tank, a pair of uprights 40 connected to the base, one of which is movable and removable, said uprights adapted

to support a roll of gummed tape, a cradle pivotally mounted on the base between the uprights and the moistening roll and having a tearing edge at its forward end, devices on the cradle supporting the tape, a rod 45 connecting the respective end portions of the cradle, a movable weight on the rod, cushions on the rod receiving the impact of the weight, cushions on the base receiving the impact of the cradle, a bail pivotally connected to the cradle, and a roller carried by the free end of the bail and constituting an automatic drop adapted to engage the free portion of the tape and to hold it away from the tearing edge.

50 8. A machine of the character described, comprising a base, a box at one end of the base, a liquid tank in the box, a moistening roll in the liquid tank, a pair of uprights 55 connected to the base, one of which is movable and removable, said uprights adapted to support a roll of gummed tape, a cradle pivotally mounted on the base between the uprights and the moistening roll and having a tearing edge at its forward end, devices on the cradle supporting the tape, a rod connecting the respective end portions of the cradle, a movable weight on the rod, 60 cushions on the rod receiving the impact of the weight, cushions on the base receiving the impact of the cradle, a bail pivotally connected to the cradle, a roller carried by the free end of the bail and constituting an automatic drop adapted to engage the free portion of the tape and to hold it away 65 from the tearing edge, and an angle bracket fixed to the cradle to limit the rearward movement of the bail.

70 JOSEPH HENRY McINTIRE.
